UNITED STATES PATENT OFFICE.

JULIUS D. HAYNSWORTH, OF MANSFIELD, OHIO, ASSIGNOR TO WESTINGHOUSE ELECTRIC PRODUCTS COMPANY, A CORPORATION OF MICHIGAN.

ELECTRIC HEATER.

Application filed May 14, 1921. Serial No. 469,441.

To all whom it may concern:

Be it known that I, JULIUS D. HAYNSWORTH, a citizen of the United States, and a resident of Mansfield, in the county of Richland and State of Ohio, have invented a new and useful Improvement in Electric Heaters, of which the following is a specification.

My invention relates to electrically heated apparatus and particularly to electric heaters and it has for its object to provide a relatively simple, compact and rugged electric heater which may be used in rooms or spaces filled with an explosive or inflammable mixture.

In practising my invention, I provide an electric-resistance element which is mounted in a perforated casing, with a wire screen of relatively fine mesh located inside of said casing and surrounding said heating element, to prevent the travel of any inflammable mixture which has been ignited by the heated resistance element beyond the wire screen.

The device disclosed in the present application is an improvement on that disclosed in Serial No. 343,896, filed Dec. 10, 1919, by F. Thornton, jr., and assigned to the Westinghouse Electric Products Company.

Referring to the single sheet of drawings, Figure 1 is a view in front elevation, certain parts being broken away, and

Fig. 2 is a view, in vertical cross-section, on the line II—II of Fig. 1.

A heating element, indicated generally by 1, comprises a perforated metal casing 2 of substantially tubular shape, the overlapping ends of which may be welded or brazed together in a manner well known in the art.

One end of the tubular member 2 is provided with a head 3 in which is located an opening 4, a threaded metal sleeve 5 being located adjacent the head 3 and the opening 4 and suitably secured to the head 3 by spinning over the metal, or by soldering.

At the other end of the member 2, I provide an imperforate head 6, which may have a down-turned flange portion 6^a, within which the end of the member 2 may be located, the two members being suitably secured together.

The heating means comprises a refractory terminal block 7, suitably cored to receive two contact terminals 7^a adapted to cooperate with a suitable plug member (not

shown) for connection to a supply circuit, in the usual manner. Located adjacent to the member 7 is a spacing member 8 which is adapted to co-operate with a tubular refractory member 9 on which a resistor wire 10 is wound. An end member 11 is located at the other end of the tubular member 9, both the members 8 and 11 being provided with a reduced portion 12 adapted to interfit with the member 9 to maintain them substantially coaxial.

In order to maintain the members 7, 8, 9 and 11 in proper operative relation, I provide a threaded bolt 13, at one end of which a nut 14 is located in a cored out portion of the member 7. A nut 15 is screwed on the rod 13 to engage the member 11 and thus press the members 7, 8, 9 and 11 together, substantially in the position indicated in the drawing.

In order to hold one end of the heating means in the casing, I provide a suitable metallic casing 16 which engages a shoulder portion of the member 7 and projects sufficiently beyond the contact terminals 7^a to substantially surround them. A threaded metallic sleeve member 17, having an in-turned flange portion 18, is provided, the internal diameter of the flange portion 18 being such as to permit of the placing of the member 17 over the casing 16 and of then so turning it as to cause it to take the position indicated in Fig. 2 to securely hold the member 7. The other end of the resistor means is held in its proper operative position in the casing 2 by the other end of the bolt 13, which projects through a suitable opening 19 substantially in the center of the head 6, being clamped thereto by means of a plurality of nuts 20.

A hook member 21 is suitably secured to the casing 2 to permit of hanging the heating element upon a suitable support if desired.

If this type of heater is used to maintain the temperature of a radiator of an automobile substantially above the freezing point, by being energized while located under the hood of the car, it is possible that gasoline vapors may be generated which may be ignited when the temperature of the resistor 10 becomes relatively high. In order to prevent this action, I provide a wire screen 22 of relatively fine mesh located inside of the casing 2 and surround-

ing the resistor. I may provide annular members 23 at the ends of the casing 2 to permit of clamping or screwing the screen to the casing, the members being suitably riveted together.

The function of the device embodying my invention, will be understood to consist primarily in preventing the passage of any flame that may result from the contact of 10 small quantities of inflammable vapors, which may find their way through the casing 2 and the screen 22, with the resistor 10 when heated to such a temperature as will cause it to glow.

15 However, I have found another application for a heater of the type described above, particularly in rooms or enclosed spaces in which a dust may be liberated which becomes explosive when combined with air in 20 certain proportions or even in rooms in which dry explosives are handled or stored. It is not necessary, in the latter case, that the temperature of the heating element be so high as to cause it to glow, as is necessary 25 in the case of explosive vapors, as such explosive mixtures may become ignited or be exploded by an open resistor element which is at a temperature below that which would cause it to glow.

The use of the device embodying my invention effectively prevents the spread of 30 the burning vapor and probably prevents the explosive mixtures or dust from getting into direct contact with the exposed resistor, hence my device provides a safe heating element which may be used where explosive mixtures of any kind are present.

Various modifications may be made in the device embodying my invention without departing from the spirit and scope thereof 40 and I desire that only such limitations shall be placed thereon as are limited by the prior art or are specifically set forth in the appended claim.

45 I claim as my invention:

An electric heating means for use in explosive-vapor-filled rooms comprising a resistor member adapted to be heated substantially to incandescence, a perforated cylindrical casing surrounding said resistor 50 member, imperforate heads secured to said cylindrical casing, and a substantially tubular fine-mesh screen inside of said casing and having its ends secured thereto.

55 In testimony whereof, I have hereunto subscribed my name this 11 day of May, 1921.

JULIUS D. HAYNSWORTH.
